UNITED STATES PATENT OFFICE.

LE ROY CHURCHILL CHOWNING, OF CORNING, NEW YORK.

TIMER FOR INTERNAL-COMBUSTION ENGINES.

949,392.

Specification of Letters Patent. Patented Feb. 15, 1910.

Application filed June 3, 1909. Serial No. 499,852.

To all whom it may concern:

Be it known that I, LE ROY CHURCHILL CHOWNING, a citizen of the United States, residing at Corning, in the county of Steuben and State of New York, have invented certain new and useful Improvements in Timers for Internal-Combustion Engines, of which the following is a specification.

This invention relates to improvements in the timing devices for controlling the electric spark producing apparatus by which the charges in the engine cylinders are ignited; and the object of my invention is to produce a timing device which will be positive in operation; in which all the parts will be exposed for inspection and lubrication; and in which the wear will be reduced to a minimum.

I attain my object by constructing the timer in the manner illustrated in the accompanying drawings, in which—

Figure 1 represents a vertical longitudinal section through my timing device, on the line *a—a* in Fig. 2; Fig. 2, an end view of the timer; Fig. 3, a plan view thereof; and Figs. 4 and 5, details showing the rocker arm, and one of the contact rings, respectively.

Like numerals designate like parts in the several views.

This timer is designed to be applied to an engine cam shaft, 1, where it projects through the bearing 2. It consists of a bushing 3, provided with a shoulder 4 at its inward end, and fastened to the cam shaft by means of a set screw 5. Upon this bushing rings 6, 7, 8, and 9, of vulcanized fiber, or other suitable nonconducting material, are mounted, the ring 8 being of smaller diameter than the other rings, to receive a brass ring 10, all the rings being fastened upon the bushing by means of the nut 11. As thus arranged, the timer is designed for a three cylinder engine; it being understood that there will be more or less of the rings 6, 7, and 9, according to the number of cylinders on the engine. Each of these rings 6, 7, and 9, is provided with a contact block 12, which is placed in electrical connection with the brass ring 10 by means of screws 13, the screws for the blocks on the rings 6 and 7 being passed through said rings and into the brass ring 10 upon the left hand side of Fig. 1. The rings 6, 7, and 9, will be so positioned on the bushing as to locate the contact blocks 12, carried thereby,

at angular distances of 120°, to correspond with the engine crank positions. Roller brushes 14 rest upon the perimeters of the rings 6, 7, 10, and 9, said rollers being mounted in arms 15, pivoted upon a rod 16, fastened to the rocker arm 17; by the adjustment of which arm the sparks may be advanced or retarded. This rocker arm is carried upon a ring 18, which in turn is mounted upon a flanged ring 19, screwed fast to the outer face of the bearing 2, around the cam shaft; and the rocker arm is held in adjustment by means of a set screw 20.

The hubs of the arms 15 are bushed with fiber or other nonconducting material, as shown at 21 in Fig. 3, where one of the hubs is shown in section, and between the hubs on the several arms fiber washers 22 are inserted to insulate the arms from one another. At 23 the hubs are provided with binding screws, whereby the wires 24, which lead to the spark plugs on the cylinders 25, are electrically connected with the roller brushes 14. The arm which carries the roller brush in contact with the brass ring 10 is connected with the wire 26 which runs to the dynamo or other source of electricity, the circuit between the dynamo and the cylinders 25 being made by ground or wire connections, as indicated by the wire 27. Thus, as each contact block 12 passes beneath a roller brush 14, the circuit is closed, for producing a spark in that particular cylinder, through the ring 10, the screws 13, and the blocks. The roller brushes are held in contact with the rings by means of springs 28 which press downward upon the arms 15, said springs encircling pins 29, which project upward from said arms through insulating bushings 30 in the guide bar 31, which bar is fastened to a branch 32 of the rocker arm 17. The upper ends of the springs 28 bear against washers which engage the bushings 30.

The rings, when assembled, form in effect a cylinder of insulating material in which the several contacts are embedded, the separate rings being used for facilitating manufacture and adjustment.

Instead of the continuous circuit closing ring contact 10, I might set into the cylinder separate ring sections, or blocks, similar to the make-and-break contact blocks, placing a section opposite each make-and-break contact and connecting it therewith by a screw 13.

As so constructed, all the parts of the timer are open for inspection, and the adjustment to advance or retard the sparks is easily reached and readily manipulated.

5. Friction is reduced to a minimum, and there can be no sparking between the brushes and the contact blocks. The bearings are all within reach for oiling; and the life of the timer is practically unlimited.

10. What I claim as my invention and desire to secure by Letters Patent is—

1. The combination, with an internal combustion engine, of a timer comprising a plurality of make and break contacts mounted in a revoluble cylinder of insulating material to rotate in separate annular paths, said contacts being set in angular adjustment to one another around the cylinder in conformity with the engine crank positions and exposed at the surface of the cylinder, a circuit closing contact mounted in the cylinder to rotate in a path separate from the other contacts but in electrical connection with them, brushes held in contact with the cylinder in the line of travel of the several contacts, said brushes being insulated from one another, and electrical connections leading from the brushes for the make and break contacts to the engine spark plugs and from the brush for the circuit closing contact to a source of current supply.

2. The combination, with an internal combustion engine, of a timer comprising a plurality of make and break contacts mounted in a revoluble cylinder of insulating material to rotate in separate annular paths, said contacts being set in angular adjustment to one another around the cylinder in conformity with the engine crank positions and exposed at the surface of the cylinder, a circuit closing contact mounted in the cylinder to rotate in a path separate from the other contacts but in electrical connection with them, brushes held in contact with the cylinder in the line of travel of the several contacts, said brushes being insulated from one another, electrical connections leading from the brushes for the make and break contacts to the engine spark plugs and from the brush for the circuit closing contact to a source of current supply, and means for setting the brushes forward or back around the cylinder axis to advance or retard the sparks.

3. The combination, with an internal combustion engine, of a timer comprising a plurality of make and break contacts mounted in a revoluble cylinder of insulating material to rotate in separate annular paths, said contacts being set in angular adjustment to one another around the cylinder in conformity with the engine crank positions and exposed at the surface of the cylinder, a circuit closing contact mounted in the cylinder to rotate in a path separate from the other contacts but in electrical con-

nexion with them, roller brushes carried by arms mounted on a support positioned parallel to the axis of the cylinder, said arms being insulated from one another and from the support, and electrical connections leading from the brushes for the make and break contacts to the engine spark plugs and from the brush for the circuit closing contact to a source of current supply.

4. The combination, with an internal combustion engine, of a timer comprising a plurality of make and break contacts mounted in a revoluble cylinder of insulating material to rotate in separate annular paths, said contacts being set in angular adjustment to one another around the cylinder in conformity with the engine crank positions and exposed at the surface of the cylinder, a circuit closing contact mounted in the cylinder to rotate in a path separate from the other contacts but in electrical connection with them, roller brushes carried by arms mounted on a support positioned parallel to the axis of the cylinder, a rocker arm from which said support projects, means for setting the rocker arm forward or back around the cylinder axis, and electrical connections leading from the brushes for the make and break contacts to the engine spark plugs and from the brush for the circuit closing contact to a source of current supply.

5. The combination, with an internal combustion engine, of a timer comprising a plurality of make and break contacts mounted in a revoluble cylinder of insulating material to rotate in separate annular paths, said contacts being set in angular adjustment to one another around the cylinder in conformity with the engine crank positions and exposed at the surface of the cylinder, a circuit closing contact mounted in the cylinder to rotate in a path separate from the other contacts but in electrical connection with them, roller brushes carried by arms pivotally mounted on a support positioned parallel to the axis of the cylinder, a rocker arm from which said support projects, a bar projecting from the rocker arm over the brush arms, springs positioned between said bar and the arms to press the roller brushes against the cylinder, means for setting the rocker arm forward or back around the cylinder axis, and electrical connections leading from the brushes for the make and break contacts to the engine spark plugs and from the brush for the circuit closing contact to a source of current supply.

6. The combination, with an internal combustion engine, of a timer comprising a plurality of rings of insulating material, means for fastening said rings one against another upon the cam shaft of the engine, make and break contacts on said rings, said contacts being set in angular adjustment to one another around the shaft in conformity with

the engine crank positions, a circuit closing contact on one of the rings in electrical connection with the other contacts, brushes held in contact with the cylinder in the line of travel of the several contacts, said brushes being insulated from one another, and electrical connections leading from the brushes for the make and break contacts to the engine spark plugs and from the brush for 5 the circuit closing contact to a source of current supply.

7. The combination, with an internal combustion engine, of a timer comprising a bushing adapted to be fastened upon the 10 engine cam shaft, a plurality of rings of insulating material fastened one against another upon said bushing, make and break contacts on said rings, said contacts being set in angular adjustment to one another 15 around the shaft in conformity with the engine crank positions, a circuit closing 20

contact on one of the rings in electrical connection with the other contacts, a rocker arm mounted on the cam shaft bearing to turn around the shaft, means for fastening 25 the rocker arm in desired positions around the shaft, brushes mounted on a support projecting from the rock arm parallel to the shaft, said brushes contacting with the several rings and being insulated from one another, and electrical connections leading 30 from the brushes for the make and break contacts to the engine spark plugs and from the brush for the circuit closing contact to a source of supply. 35

In testimony whereof I have affixed my signature, in presence of two witnesses.

LE ROY CHURCHILL CHOWNING.
